UNITED STATES PATENT OFFICE

133,989

DESIGN FOR A BOOK END

Frank C. Block, Kenosha, Wis.

Application August 22, 1942, Serial No. 107,998

Term of patent 3½ years

To all whom it may concern:

Be it known that I, Frank C. Block, a citizen of the United States of America, and residing at Kenosha, in the county of Kenosha and State of Wisconsin, have invented a new, original, and ornamental Design for a Book End, of which the following is a specification, reference being had to the accompanying drawing, forming a part thereof.

In the drawing:

Fig. 1 is a side elevational view of a book end, showing my new design;

Fig. 2 is an end elevational view; and

Fig. 3 is a top plan view thereof.

I claim:

The ornamental design for a book end, as shown.

FRANK C. BLOCK.
